UNITED STATES PATENT OFFICE.

WALTER DONGAN WOOD, OF ALLENTOWN, PENNSYLVANIA, ASSIGNOR, BY MESNE ASSIGNMENTS, TO FULLER LEHIGH COMPANY, A CORPORATION OF DELAWARE.

FLUE-SHEET CLEANER.

Application filed August 20, 1921. Serial No. 493,857.

This invention relates to an apparatus for cleaning the flue sheet of a boiler, and in particular involves the provision of an apparatus of this character utilizing high pressure or live steam for removing or preventing the accumulation of fused ash, known as honeycomb, or other substances which adhere to the flue sheet particularly in boilers using pulverized fuel.

In practice it is found that the tendency for honeycomb to form on the flue sheet of a boiler fired by pulverized fuel is quite marked, especially where the boiler is operated at high rates of evaporation as is usual for instance in locomotives in which, in addition to severe working conditions involving large fuel consumption, the fire box is necessarily small so that the particles of fused ash reach the flue sheet before they can be solidified by cooling and so, being in the molten condition, adhere to the surface of the flue sheet. The honeycomb formation resulting from this deposit of molten slag builds up more rapidly in the vicinity of the boiler tubes, the particles settling at the junction between the flue sheet and the boiler tubes and building up in the inlet openings of the tubes soon clogging or completely blocking them to the passage of the furnace gases, thus decidedly lowering the efficiency of the boiler. This trouble is widely experienced in pulverized fuel boiler practice both in stationary and locomotive boilers, and the present practice is to remove the accumulations of slag or honeycomb by means of a long bar or a hand operated steam lance after the honeycomb has accumulated to an amount where boiler tubes are badly clogged or stopped up and attention must be given to the removal of the honeycomb because of lowered boiler efficiency.

The invention provides apparatus for not only preventing the accumulation but also removing a deposit of honeycomb by utilizing high pressure or live steam from the boiler or other source which is directed, preferably in the form of jets, against the honeycomb deposit on the surface of the flue sheet as often as may be required, and while the boiler is in full operation.

In the preferred form of embodiment of the invention, the apparatus includes means for admitting steam to one of the flues of the boiler, in which flue there is mounted a device having a movable part which is

forced partly out of the flue by steam pressure. This movable part is provided with steam orifices through which the steam admitted to the flue escapes in the form of jets directed against the flue sheet. Preferably this movable part takes the form of a hollow plunger provided with means by which the plunger is normally held within the flue spaced from the end thereof, and the plunger is exposed to the pressure of the steam admitted to the flue and forced out of the flue to a position in which the orifices permit the escape of the steam. In addition, the mechanism includes means lying within the flue and preventing dust and gases from entering the flue, thus preventing accumulations of solid material which would prevent the operation of the plunger, and the device also includes means within the flue which close the orifices when the plunger is in retracted position, thus preventing the escape of the steam should the steam not be entirely cut off.

For a better understanding of the invention, reference will be had to the accompanying drawings, in which

Fig. 1 is a sectional view of one form of the apparatus,

Fig. 2 is a view on the line 2—2 thereof,

Figs. 3 and 4 are views of modified forms of the apparatus.

Other features of the invention, and particularly specific features of construction in the preferred embodiments of the invention will appear from a description of these embodiments given hereinafter in connection with the drawings.

In the apparatus illustrated the elements for conducting steam through certain of the flues or boiler tubes 10 to the flue sheet 19 are actuated by the pressure of the steam to move them rearwardly or outwardly in the flues so as to cause the end of each of the elements to project outside the end of the flue in position to permit steam to issue therefrom and sweep along the surface of the flue sheet to effect the cleansing action. In the form of construction illustrated in Fig. 1 the flue or boiler tube 10 has at one end a cap 37 welded to the interior of the tube in which is a threaded opening 38 for receiving the threaded end of the pipe 9. Mounted within the tube is a sleeve 39 secured therein by means of welding as at

40. The sleeve 39 is of two diameters providing a shoulder 41, and has a screw threaded connection with a plug 42 fitted within the tube. Mounted within the sleeve 39 is a plunger 43 having a flange 44 between which and the shoulder 41 of the sleeve is a coil spring 45 surrounding the outside of the plunger. The rear end 46 of the plunger is open and aligns with an opening 47 in the plug 42, while the outer end 48 of the plunger is closed. Adjacent its closed end 48 the plunger is provided with circumferentially disposed orifices 50 which are inclined to the axis of the plunger and rearwardly thereof, as well as being inclined to the surface of the plunger. When the fireman desires to clean the flue sheet, he opens a valve controlling the flow of steam through the line 9. The steam passes through the opening 47 in the plug 42 into the plunger 43 and the pressure of the steam forces the plunger rearwardly or to the left in Fig. 1, compressing the spring 45 until the end of the plunger and particularly the orifices therein project outside the tube to permit the escape of steam from the plunger and against the outside surface of the flue sheet 19. As long as the steam is supplied to pipe 9, it holds the plunger in its operative position, but as soon as the steam supply is shut off the plunger is returned to its normal position within the tube by the spring 45, this normal position being illustrated in Fig. 1, in which position the plunger is protected against burning out by prolonged subjection to the direct action of the heat of the fire box. Moreover, the plunger 43 and its flange 44 closely fit the cylinder walls 49 of the sleeve 39 so that the hot furnace gases are excluded from those of the boiler tubes employed for the cleaning apparatus through which the gases would otherwise pass, and so the parts of the apparatus contained within the tubes are protected against burning out by the action of the furnace gases. From the foregoing description of the operation it will be seen that the action of the apparatus after the opening or closing of the valve 29 is entirely automatic.

50. The modified forms of construction of parts of the cleaning apparatus illustrated in Figs. 3 and 4, correspond to those in Fig. 1 and are identical in operation with the latter. Instead, however, of connecting the pipe 9 directly with a cap at the end of the boiler tube, in the form of construction illustrated in Fig. 3 an extra piece of piping 51 is provided which is threaded at one end into the plug 42 and is supported near its opposite end by means of a retaining collar 52 which is welded to the piping 51 as at 53. The pipes 51 and 9 are joined by means of a coupling 54 and the retaining collar 52 is secured to the front tube sheet 55 by means of a screw and nut 56. In this construction

both the sleeve 39 and the plug 42 are loosely mounted within the tube, although closely fitting the latter, the sleeve and plug being adjusted to position within the tube by means of a retaining collar 52 and the pipe 51 which the retaining collar supports and with the end of which the plug 42 has threaded connection. The sleeve 39 and plug 42 will, therefore, be held against movement due either to the pressure of furnace gases in one direction or steam in the other, or movement with the plunger 43 under the action of steam admitted to the latter. By employing a construction such as that illustrated in Fig. 3, the pipe 51, plug 42, plunger 43 and the sleeve 39 may all be removed for inspection and repair from the forward end of the tube simply by disconnecting the pipes 51 and 9, and loosening the nut and screw 56 holding the retaining collar to the front tube sheet 55.

In Fig. 4, the construction and assembly of the parts are such that the plunger 43 and spring 45 may be removed for inspection and repair from the rear end of the tube 10, that is the end adjacent the flue sheet. The sleeve 39 is made in two pieces, a rear piece 39^A and a front piece 39^B, having screw threaded connection as at 57. The outer end of the piece 39^A is provided with notches 58 for receiving a wrench which may be inserted in the end of the tube for disconnecting the pieces 39^A and 39^B. The inner end of the piece 39^A provides a shoulder 59 against which one end of the spring 45 abuts, so that when this piece is removed the spring which holds the plunger 43 within the sleeve 39 is released and the plunger and spring may, therefore, be taken out. Here the pipe 9 is threaded directly into the threaded front end of the piece 39^B, the pipe being adjustably supported by a retaining collar 52 as in the construction illustrated in Fig. 3.

In the operation of the steam conducting elements illustrated in Figs. 1-4, when the plunger 43 is forced rearwardly or outwardly until the orifices 50 clear the end of the flue, steam issues from these orifices and is directed backwardly against the flue sheet 19 due to the backward inclination of the orifices. In addition to this inclination, the orifices 50 are also inclined to the surface of the plunger, as illustrated in Fig. 2, and so when the plunger is advanced by the steam pressure to its operative position outside the flue, and before it reaches this position the fit between the plunger and the forward cylinder wall 49 should be such as to permit steam to issue within the sleeve, the plunger will be slightly rotated during its forward movement depending upon the direction of inclination of the orifices, in the present instance the direction of rotation being counter clockwise as will be evident from Fig. 2. This slight rotating movement is given to the plunger each time it advances

to operative position and thus the jets of steam will gradually be rotated through complete circles covering the entire surface of the flue sheet within the zone of action of the steam jets. These jets issuing from the various plungers distributed at different points in the bank of boiler tubes, and having rotative movement imparted thereto, will intersect or combine to cover the entire surface of the flue sheet and effectively cut and remove therefrom any deposit of honeycomb.

I claim:

1. In a boiler having a flue sheet and a plurality of flues, the combination of a device mounted movably in a flue and normally lying within the flue at a distance from the end thereof, a plurality of orifices formed in the end of the device, means within the flue for closing these orifices when the device is in its normal inner position, means for introducing steam under pressure into the device, the steam acting to move the device to a position in which the orifices lie beyond the flue sheet, and means within the flue for restoring the device to its original position when the steam pressure is off.

2. In a boiler having a flue sheet and a plurality of flues, the combination of a device mounted movably in a flue and normally lying within the flue at a distance from the end thereof, a plurality of orifices formed near the end of the device, means in the flue for closing the orifices when the device is in its normal inner position, the said means cooperating with the device to prevent the passage of gases from the furnace through the flue, and means for introducing steam under pressure into the device, the steam serving to move the device in the flue to a position in which the orifices lie beyond the flue sheet.

3. In a boiler having a flue sheet and a plurality of flues, the combination of means for conducting steam to a flue of the boiler, a device permanently mounted within the flue and adapted to conduct steam therethrough to the flue sheet, the device being movable out of the flue under the action of the steam, orifices near the end of the device lying beyond the flue sheet when the device is in its exposed position and providing outlets for the passage of steam which is directed thereby against the flue sheet, means within the flue for closing the orifices when the device lies in its normal inner position, the said means cooperating with the device to prevent the passage of gases from the furnace through the flue, and means within the

flue for restoring the device to its normal retracted position within the flue.

60

4. In a boiler having a flue sheet and a plurality of flues, the combination of means for admitting steam from the boiler to one of the flues thereof, a sleeve lying within the end of the flue, a hollow plunger movable within the sleeve, and a spring tending to hold the plunger in the sleeve spaced inwardly from the end of the flue, the plunger having its forward end closed and being provided with a plurality of orifices for the escape of steam formed in the side walls adjacent this end, these orifices being closed by the sleeve when the plunger lies in normal position within the flue.

70

5. In a boiler having a flue sheet and a plurality of flues, the combination of a sleeve mounted in one of the boiler flues, a plunger movably mounted in the sleeve and having a closed end, a plurality of apertures disposed in the side wall of the plunger and normally closed by the sleeve, and a pipe for admitting steam to the interior of the plunger to move the latter to a position in which said apertures are exposed beyond the end of the sleeve.

75

6. In a boiler having a flue sheet and a plurality of flues, the combination of a sleeve mounted in one of the boiler flues, a plunger movably mounted in the sleeve, a plurality of apertures formed in the side wall of the plunger and normally closed by the sleeve, means for admitting steam to the interior of the plunger to move the latter to a position in which said apertures are exposed beyond the end of the sleeve, and means within the sleeve and tending to restore the plunger to normal position.

85

7. In a boiler having a flue sheet and a plurality of flues, the combination of a sleeve mounted in one of the boiler flues, a hollow plunger freely mounted within the sleeve and having a closed end, a plurality of apertures in the side wall of the plunger adjacent said closed end, these apertures being normally closed by the sleeve and having an inclination with respect to the axis of the plunger, and means for admitting steam to the plunger to move the latter through the sleeve to a position in which the apertures are exposed, the escape of steam through the apertures when the plunger is in such position producing a rotary movement of the plunger.
